UNITED STATES PATENT OFFICE.

JOSEPH C. SEYL, OF CHICAGO, ILLINOIS.

SANITARY WATER-CLOSET.

1,037,062.

Specification of Letters Patent. Patented Aug. 27, 1912.

Application filed July 17, 1911. Serial No. 638,886.

To all whom it may concern:

Be it known that I, JOSEPH C. SEYL, a citizen of the United States, residing at Chicago, in the county of Cook and State 5 of Illinois, have invented certain new and useful Improvements in Sanitary Water-Closets, of which I do declare the following to be a full, clear, and exact description, reference being had to the accompanying 10 drawing, forming part of this specification.

The present invention has for its object to provide improved means whereby there will be avoided the danger of contagion incident to the use by many persons of the 15 same closets.

To this end the invention consists in the features of novelty hereinafter described, illustrated in the accompanying drawing and particularly defined in the claims at 20 the end of this specification.

Figure 1 is a plan view showing my invention applied to a water closet bowl of familiar form. Fig. 2 is a view in side elevation.

25 In the drawing, I have shown part only of a closet bowl A as the bowl forms no part of the invention, which may be applied to any suitable or familiar type of bowl. To the rear upper surface of the 30 bowl A are fixed the standards B, the sockets of which receive the ends of the pivot rod C whereby the seat of the closet may be pivotally supported. As shown, the rod C passes through the lugs d that project rear- 35 wardly from the metal supporting bar D and are preferably formed integral therewith. This bar D is of approximately semi-circular shape and its ends set within recesses formed in the underside of the seat 40 members E which are securely held upon the bar D by screws d'. Beneath the bar D and on top of the bowl A are mounted the plates D' that carry the rubber buffers d' whereon the seat members E will rest when 45 in position for use, these plates D' being held in place by the stems of the standards B that pass through them. The outer ends of the seat members E may also be provided with rubber buffers e to contact with the 50 front portion of the bowl rim.

As shown, each of the seat members E is formed from a straight flat bar of wood, the upper and inner portions of which are shaped to conduce to the comfort of the 55 user. The seat members E are, preferably, diagonally disposed with respect to each

other, their inner ends being more widely separated than their outer ends.

Opposite the rear end of each of the seat members E is placed a paper receptacle F. Preferably, each of the paper receptacles F is of a shape and size adopting it to hold a roll of toilet paper; and the discharge orifice of each paper receptacle is at right angles to the seat member E at the rear of which it is mounted and approximately on a line with the upper surface of such member. At the discharge orifice of each paper receptacle F there is a supporting plate f and, above this plate, a cutting strip or blade f' whereby the sections of paper may be severed from the roll. In order to enable the end of the paper to be readily advanced after a section of the paper has been torn away, I form each cutting blade or strip f' 75 with an open space f² through which the paper may be reached by the finger and moved beyond the front edge of the cutting blade or strip f' when the strip of paper can be pulled out to the required extent. 80

From the foregoing description it will be seen that when the closet is to be used the strips of paper (indicated in dotted lines at g) will be drawn outward a sufficient extent to cover each of the seat members E and thus protect the skin of the occupant from contact therewith. After the closet has been used the strips of paper covering the seat members E can be readily severed by the cutting blades f'. 90

By forming the seat members E of straight bars of wood of substantially uniform width and diagonally disposed with respect to each other, strength and economy of construction are insured and by attaching the seat members E to the ends of the bar D, as shown, these members are most securely supported. 95

The employment of individual paper receptacles and their arrangement at the rear ends of the seat members E enables these members to be effectively covered by the paper in the most economical manner, since no more paper is used than is actually required to cover the upper surfaces of the 100 seat members. So also the plate f and the cutting blade f', arranged as they are at right angles to the seat members and in close proximity to the upper surfaces thereof, securely retain the strips of paper in position upon the seat members. Another advantage incident to the employment of the 105 110

individual paper receptacles arranged as shown is that they enable the seat to be lifted without danger of the receptacles contacting with the central rear portion of the 5 closet bowl or its fittings.

It is obvious that the details of construction above set forth may be varied without departure from the scope of the invention and that features of the invention may be 10 employed without its adoption as an entirety.

Having thus described my invention what I claim as new and desire to secure by Letters Patent, is:—

15 1. The combination with a water closet seat, comprising side members separated at their front ends, of individual paper recep-

tacles one mounted at the rear of each of said side members and having an opening through which paper may be drawn out in 20 line with said side members.

2. The combination with a water closet seat, comprising side members separated at their front ends, of individual paper receptacles one mounted at the rear of each of 25 said side members and having an opening extending at right angles to said side members through which opening paper may be drawn out in line with said side members.

JOSEPH C. SEYL.
